US0D1099788S

(12) **United States Design Patent** (10) **Patent No.:** **US D1,099,788 S**
(45) **Date of Patent:** **** Oct. 28, 2025**

(54) **VEHICLE FRONT LOWER GRILLE**

(71) **Applicant:** **GM GLOBAL TECHNOLOGY OPERATIONS LLC**, Detroit, MI (US)

(72) **Inventor:** **Vincent D. Kaptur, IV**, Farmington Hills, MI (US)

(73) **Assignee:** **GM GLOBAL TECHNOLOGY OPERATIONS LLC**, Detroit, MI (US)

(**) **Term:** **15 Years**

(21) **Appl. No.:** **29/956,186**

(22) **Filed:** **Aug. 6, 2024**

(51) **LOC (15) Cl.** **12-16**

(52) **U.S. Cl.**

USPC **D12/169**; D12/163

(58) **Field of Classification Search**

Primary Examiner — George D. Kirschbaum

Assistant Examiner — John P. Mccartney

(57) **CLAIM**

The ornamental design for a vehicle front lower grille, as shown and described.

DESCRIPTION

FIG. 1 is a front and left side perspective view of a vehicle front lower grille showing my new design;

FIG. 2 is a front elevation view of the vehicle front lower grille of FIG. 1;

FIG. 3 is a left side elevation view thereof;

FIG. 4 is a right side elevation view thereof;

FIG. 5 is a back elevation view thereof;

FIG. 6 is a top plan view thereof; and,

FIG. 7 is a bottom plan view thereof.

The broken lines in the drawings depict portions of the vehicle front lower grille that form no part of the claimed design.

1 Claim, 7 Drawing Sheets
